US00D860716S

(12) **United States Design Patent** (10) Patent No.: **US D860,716 S**
(45) Date of Patent: **** Sep. 24, 2019**

(54) **CONTAINER LID**(71) Applicant: **YETI Coolers, LLC**, Austin, TX (US)(72) Inventors: **Edward Abante**, Austin, TX (US);
Steve Charles Nichols, Austin, TX (US)(73) Assignee: **YETI Coolers, LLC**, Austin, TX (US)(***) Term: **15 Years**(21) Appl. No.: **29/598,606**(22) Filed: **Mar. 27, 2017**(51) LOC (12) Cl. **07-99**

Primary Examiner — Garth Rademaker*Assistant Examiner* — Katelin G Kloberg(74) *Attorney, Agent, or Firm* — Banner & Witcoff, Ltd.(57) **CLAIM**

The ornamental design for a container lid, as shown and described.

DESCRIPTION

FIG. 1 is a front perspective view of a container lid showing our new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is an exploded front perspective view thereof.
